CLAIM

The ornamental design for an indoor wall with built-in home appliances, as shown and described.

DESCRIPTION

FIG. 1 is a front perspective view of the indoor wall with built-in home appliances showing our new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view showing the use state that the widgets are displayed on the front center upper cover of the claimed design.

The broken line showing in the drawings is included for the purpose of illustrating portions of the indoor wall with built-in home appliances and forms no part of the claimed design.
